UNITED STATES PATENT OFFICE.

ROBERT E. GODFREY, OF NEW YORK, N. Y., ASSIGNOR TO MAX SCHWARZ TEXTILE CORPORATION, OF NEW YORK, N. Y., A CORPORATION OF NEW YORK.

DESIGN FOR A TEXTILE FABRIC OR SIMILAR ARTICLE OF MANUFACTURE.

Application filed March 31, 1926. Serial No. 17,141. Term of patent 3½ years.

To all whom it may concern:

Be it known that I, ROBERT E. GODFREY, a citizen of the United States, and a resident of the borough of Manhattan, city, county, and State of New York, have invented a new, original, and ornamental Design for Textile Fabric or Similar Article of Manufacture, of which the following is a specification, reference being had to the accompanying drawing, forming a part here-

of, and showing a face view of a piece of textile fabric embodying my design. The design is intended to be repeated on the fabric as shown.

I claim:

The ornamental design for a textile fabric or similar article of manufacture substantially as shown.

ROBERT E. GODFREY.
